UNITED STATES PATENT OFFICE.

JAMES M. BASINGER, OF BUFFALO, NEW YORK, ASSIGNOR OF ONE-FOURTH
TO WILLIAM L. WHITE, OF SAME PLACE.

BUCKLE.

SPECIFICATION forming part of Letters Patent No. 361,980, dated April 26, 1887.

Application filed February 3, 1887. Serial No. 226,451. (No model.)

To all whom it may concern:

Be it known that I, JAMES M. BASINGER, of the city of Buffalo, in the county of Erie and State of New York, have invented new and 5 useful Improvements in Trace - Buckles, of which the following is a specification.

This invention relates to an improvement in that class of trace-buckles which are composed of a buckle-frame to which the hame-tug is attached and a tongue-plate formed separate from the buckle-frame and provided with a stub-tongue which engages with the trace, the tongue-plate being held in place by the buckle-frame.

15 The object of this invention is to produce a trace-buckle of this character which will be simple in construction and capable of easy adjustment on the trace, and in which the tongue is relieved from the greater portion of 20 the strain.

The invention consists of the improvements in the construction of the buckle which will be hereinafter fully set forth, and pointed out in the claims.

25 In the accompanying drawings, Figure 1 is an edge elevation of my improved buckle. Fig. 2 is a longitudinal section thereof. Fig. 3 is a side elevation of the buckle. Fig. 4 is a side elevation of the buckle-frame. Fig. 5 30 is a perspective view of the tongue-plate.

Like letters of reference refer to like parts in the several figures.

A represents the hame-tug, and B the trace.

35 C represents the buckle-frame, which is provided at its front end with a depressed cross-bar, c, to which the hame-tug is attached. The buckle-frame C is formed with a flat slotted bed or bottom composed of two end plates, d and d', and connecting-bars d'.

40 e represents a raised cross-bar, arranged at the front end of the buckle-frame, and connected with the end plate, d, by curved side bars, e'. The cross-bar e is arranged above the depressed cross-bar c, and forms, with the end plate, d, and connecting side bars, e', a loop, e'.

45 f represents a raised cross-bar arranged at the rear end of the buckle-frame, and connected with the end plate, d', by curved side bars, f', to form a loop, f'. The cross-bars e and f 50 bear against the outer side of the trace when

the latter is inserted through the loops e' and f'.

g represents the usual side loops formed on the buckle-frame C for attaching the pad-strap and girth thereto, and g' represents a loop formed on the rear cross bar, f, to which the 55 side strap is attached.

H represents the tongue-plate, which rests upon the outer side of the trace between the two cross bars e and f of the buckle-frame, and which is provided on its inner side with a 60 downwardly-projecting stub-tongue, h, which passes through the trace. The tongue-plate H is provided in front of the tongue with a depressed cross-bar, h', and downwardly-curved side bars, h', forming a loop, h', through which 65 the trace passes. The tongue-plate H is provided at its rear end with a rearwardly-projecting lip or extension, j, which engages under the rear cross-bar, f, of the buckle-frame when the tongue is engaged with the trace, and 70 protects the trace from the wear which would result from the cross-bar f rubbing against the trace.

k represents a shoulder or projection formed on the outer side of the tongue-plate, in front 75 of the extension or lip j and in rear of the tongue, and adapted to engage against the front side of the rear cross-bar, f, so that the cross-bar f forms a support for the tongue-plate, whereby the tongue is relieved from the 80 strain which is applied to it when the trace is taut. The end of the tongue engages against the front side of the end plate, d', of the buckle-frame when the shoulder k is in contact with the cross-bar f, as represented in 85 Fig. 2, so that the tongue is relieved from strain on both sides of the trace. The end plate, d', is provided in its front side with a notch or recess, l, which forms a seat for the end of the tongue. The shoulder k is grooved out on its 90 under side, as shown at k' in Figs. 2 and 5, whereby the tongue-plate can be readily seized and swung away from the trace when it is desired to lengthen or shorten the trace. Upon sliding the trace forwardly until the lip or extension j of the tongue-plate is released from the cross-bar f of the buckle-frame, the tongue-plate can be readily raised to disengage the tongue from the trace by inserting the thumb or finger nail in the undercut k' of the shoulder 95 100

k. When the tongue has been disengaged from the trace, the tongue-plate *H* is free to swing outwardly from the trace on its cross-bar *h'*, which is confined between the inner 5 side of the trace and the bars *d'* of the buckle-frame. The cross-bar *h'* of the tongue-plate being located on the outer side of the buckle-frame, the inner side of the buckle-frame is smooth and has no projecting parts which 10 would be liable to rub against the horse. The raised cross-bar *e* at the front end of the buckle-frame holds the trace close to the hame-tug and relieves the ordinary leather loop employed for this purpose.

15 I claim as my invention—

1. In a buckle, the combination, with the buckle-frame *C*, having a slotted bed and raised rear cross-bar, *f*, of a sliding tongue-plate provided with a loop through which the trace 20 passes, said tongue-plate engaging under the cross-bar *f* and resting against the outer side of the bed of the buckle-frame adjacent to the trace, substantially as set forth.

2. In a buckle, the combination, with the 25 buckle-frame *C*, having a slotted bed, a raised rear cross-bar, *f*, a raised front cross-bar, *e*, and a depressed front cross-bar, *c*, of a sliding tongue-plate provided with a loop through which the trace passes, said tongue-plate en-

gaging under the cross-bar *f* and resting against 30 the outer side of the bed of the buckle-frame adjacent to the trace, substantially as set forth.

3. In a buckle, the combination, with the buckle-frame *C*, having a slotted bed, a depressed front cross-bar, *e*, to which the hame-tug is attached, and a raised rear cross-bar, *f*, of a tongue-plate, *H*, provided with a downwardly-projecting tongue, *h*, a lip or extension, *j*, adapted to engage under the raised cross-bar *f*, and a shoulder, *k*, engaging against the 40 cross-bar *f*, substantially as set forth.

4. The combination, in a buckle, of a buckle-frame, *C*, having a slotted bed, a depressed front cross-bar for attachment to the hame-tug, raised cross-bars *ef*, formed on opposite 45 ends of the buckle-frame, a tongue-plate, *H*, formed separate from the buckle-frame and provided with a depressed loop, *h'*, a downwardly-projecting tongue, *h*, a lip or extension, *j*, engaging under the rear cross-bar, *f*, and a shoulder, *k*, engaging against the cross-bar *f*, substantially as set forth.

Witness my hand this 27th day of January, 1887.

JAMES M. BASINGER.
